UNITED STATES PATENT OFFICE

JOHN A. BELHUMEUR, OF ESMOND, RHODE ISLAND

VACUUM DEVICE

Application filed March 8, 1929. Serial No. 345,376.

This invention relates to certain new and useful improvements in vacuum devices and pertains more particularly to a device of this type used for creating a vacuum in vapor heating systems.

In systems of this type, a very low boiler pressure is utilized, so that a vapor, as distinguished from steam results, from the heating of the hot water, the vapor being sucked up through the pipes of the heating system by means of a fan or the like, and being then forced downwardly to enter the bottom of the boiler.

The primary object of the present invention is to provide a vacuum creating device in which the vapor is boosted so as to accelerate circulation thereof.

The invention further aims to provide a device of this type which has improved means for producing a vacuum and to further provide a device of this type which is of simple construction and of high efficiency in use.

In the drawings:—

Figure 1 is a longitudinal sectional view of the invention;

Figure 2 is an end elevation;

Figure 3 is a section on a line 3—3 of Figure 1, and

Figure 4 is a detail perspective view of a fragment of the rotor.

In proceeding in accordance with the present invention a base 1 is employed upon which is mounted a cylinder 2, which is closed by end walls 3. The base of the cylinder is formed with an inlet 4 and an oppositely disposed outlet 5, the inlet being located above the outlet. The rotor has a hub 6 mounted on a shaft 7 the shaft being journaled in standards 8 and may be driven by any suitable means, such as for example, pulley 9. The rotor is provided with straight arms 10 which latter extend diametrically of the rotor and have a substantially right angular relation, or otherwise stated are of cruci-form. Curved vanes 11 extend outwardly from each of the arms 10 at points intermediate the ends or substantially at the center of the arms, and to the inner circumference of the cylinder, thus providing the rotor with large chambers 12

and with small chambers 13, which chambers it will be noted alternate. The concave sides of the curved arms confront the inlet as the arms approach the inlet so as to obtain a quick pick-up. For the purpose of supporting and strengthening the straight and the curved arms, bars 14 are employed which are connected thereto and which are of small cross section so as to lessen the capacity of the chambers as little as possible, and still obtain a strong and rigid structure. As shown in Figure 3 the side faces of the straight and curved arms 10 and 11 engage the end walls 3 of the rotor casing.

Referring to Figure 1 of the drawings, it will be seen that a relief port 15 is provided and which is located above the inlet 4. Preferably, a pressure indicator or gage 16 is employed and is connected to the inlet 4. A valve 17 is also connected to the relief port 15. At 18 is indicated a pipe which latter is connected to the heating system and is connected to the inlet 4. A similar pipe 19 is connected to the outlet 5 and constitutes a return riser which carries the condensed vapor downwardly and into the bottom of the boiler.

The rotor is usually revolved at a high rate of speed and accordingly at periods becomes what is known as airbound. When this occurs the valve 17 is opened permitting air to flow in and slightly cool the parts, or water may be used for this purpose and be admitted through the valve 17 if desired. The object, of course, is to create a vacuum at the top of the system so as to cause lifting of the hot vapor through the system and then to discharge it by the rotor into the down flow riser to supply the boiler with the condensed water and cause reheating of the same and thereby the formation of heating vapor. By the use of large and small chambers 12 and 13 the invention not only obtains a decided lift, producing a vacuum in the inlet port, but in addition obtains a quick pick-up by the curved arms of the small chambers thus boosting the action of the vapor that has been delivered from the large chambers to the outlet chambers, and thereby accelerating circulation of vapor.

Having thus described my invention what I claim as new and desire to secure by Letters Patent is:—

1. A vacuum device of the character described comprising a cylinder having an inlet, an outlet opposite to and disposed on a plane lower than said inlet, an air relief chamber formed in said cylinder above said inlet having a valve controlled relief port, a rotor in the cylinder having a hub, a plurality of radially extending arms carried by said hub and disposed at right angles to each other, and an arm carried by each of said radially extending arms intermediate the ends of the latter and having its free end curved outwardly whereby to provide alternate large and small chambers having their inner ends closed.
2. A rotor for vacuum systems including a cylinder, a shaft in said cylinder, a rotor on said shaft having a hub, a plurality of radially extending spaced arms carried by said hub and disposed at right angles to each other, a curved arm carried by each of the first named arms intermediate the ends of the latter and having its free end curved outwardly and terminating at a point at one side of a radial line drawn centrally through the space between each pair of radially extending arms, whereby the curved arms form small chambers in conjunction with the radial arms to which the curved arms are connected and large chambers in conjunction with the succeeding radial arm.
3. A rotor for vacuum systems including a cylinder, a shaft in said cylinder, a rotor on said shaft having a hub, a plurality of radially extending spaced arms carried by said hub and disposed at right angles to each other, a curved arm carried by each of the first named arms intermediate the ends of the latter and having its free end curved outwardly and terminating at a point at one side of a radial line drawn centrally through the space between each pair of radially extending arms, whereby the curved arms form small chambers in conjunction with the radial arms to which the curved arms are connected and large chambers in conjunction with the succeeding radial arm, and a bracing bar connected to each of the radially extending arms intermediate the ends of the latter and to the free end of the adjacent curved arms.
55. In testimony whereof I have signed my name to this specification.

JOHN A. BELHUMEUR.
